CAR PULLER

William W. Sloane, Chicago, Ill., assignor to
 Goodman Manufacturing Company, Chicago,
 Ill., a corporation of Illinois

Application February 24, 1934, Serial No. 712,704

12 Claims. (Cl. 198—220)

This invention relates to improvements in car pulleys and has among other objects to provide a new and improved device of the class described of a novel, simplified, efficient and compact construction, operated and controlled in a new and improved manner, which device is particularly adapted for use with and to be driven by a conveyor of the shaker or jiggling type.

An application, Serial No. 669,928, filed May 8, 10 1933, by William E. Goodman, shows a device of the general type disclosed in my present invention. The device of my invention differs from the aforesaid prior application in certain details of arrangement and the specific means for transmitting the motion of the shaker conveyor to the winding drum.

My invention may be more clearly understood with reference to the accompanying drawings wherein:

20 Figure 1 is a side elevation of the device embodying my invention illustrating one form, and the use and operation thereof;

Figure 2 is an enlarged detail end view of the device embodying my invention with parts broken away and with parts of the winding drum shown 25 in transverse vertical section;

Figure 3 is an enlarged detail side elevation of the device shown in Figure 1 with parts broken away and in section to more clearly show the 30 details of my invention;

Figure 4 is an enlarged fragmentary isometric view of the device embodying my invention with parts broken away to more clearly show certain details thereof; and

35 Figure 5 is an enlarged detail sectional view of one of the rollers for supporting the conveyor trough.

Like reference characters refer to like parts throughout the various figures.

40 Referring now in particular to the embodiment of my invention illustrated in the drawings, a shaker conveyor pan line is provided which includes a reciprocably movable conveyor pan 10. The pan line is reciprocably driven by suitable conveyor drive mechanism in a manner well known to those skilled in the art so that material such as coal may be moved therealong in one direction for discharge into mine cars or other suitable material receiving means. As herein shown, the conveyor pan 10 is so arranged and supported as to discharge material into suitable mine cars 11 on a track 12.

45 With reference now in particular to the means for moving the cars 11 along the track 12 at a controlled rate beneath the discharge end of the

conveyor pan 10 as material is discharged therein and several novel features of my invention, a car puller, driven by the conveyor pan 10 and generally indicated by reference character 13, is provided. The car puller 13 includes a shoe 14, 50 which is herein shown as being a relatively flat plate of a substantially rectangular outline having upturned ends and being adapted to rest on the ground or mine bottom. The shoe 14 is adapted to be held in position on the bottom by 55 means of screw jacks 15, 15 of an ordinary construction interposed between said shoe and the mine roof and having their lower ends resting in suitable recesses formed in said shoe (not shown). A cross member 16 is provided for connecting the screw jacks 15, 15 together. The cross member 16 is supported in brackets 17, 17 adapted to be adjustably mounted on the screw jacks 15, 15 by means of U-bolts 18, 18 in a suitable manner so that said cross member may form 70 an adjustable support for the conveyor trough 10 for permitting said trough to be supported for reciprocable movement with respect thereto in various elevations with respect to the ground to accommodate the discharge end of said trough 75 to various heights of mine cars and conditions of loading.

80 A pair of support members 19, 19 are adjustably secured to the cross member 16 and extend upwardly therefrom. Each of the support members 19 forms a support means for an anti-friction roller device 20 secured thereto by means of a stud 21 formed integral with the inner race of said roller device. The anti-friction roller devices 20, 20 are arranged to engage the under 85 side of the conveyor pan 10 for supporting said conveyor pan for reciprocable movement with respect to the cross member 16.

85 The shoe 14 is provided with a pair of parallel spaced upstanding support members 22, 22 which provide a support for a shaft 23 adjacent its ends. The shaft 23, as herein shown, is held from rotation by means of a plate 25a engaging a suitable groove formed in said shaft and is so arranged 90 as to extend longitudinally of the conveyor pan 10. A winding drum 24 is freely mounted on the shaft 23 for rotation with respect thereto. The winding drum 24 is provided with an annular flanged portion 26 extending perpendicular to one of its flanges, which annular flanged portion 100 has ratchet teeth 27, 27 cut integral therewith. An annular flanged portion 28 extends outwardly from the opposite flange of the winding drum 24 and has ratchet teeth 29 formed integral with its outer periphery. The ratchet teeth 27 are 105 110

adapted to be engaged by pawl 30 pivotally connected to one lever arm 32 of a bell crank member 33. The bell crank member 33 is journaled on the shaft 23 for pivotal movement with respect thereto in a suitable manner so that upon rocking movement of said bell crank member, engagement of the pawl 30 with the ratchet teeth 37 will impart rotational movement to the winding drum 24 when the lever arm 32 moves in one direction. The ratchet teeth 29 are adapted to be engaged by a dog 34 pivotally carried by an upstanding support member 35 stationary with respect to said winding drum so that engagement of the dog 34 with the ratchet teeth 29 will prevent rotation of the winding drum 24 in an opposite direction to which it is normally driven by the pawl 30.

A lever arm 36 of the bell crank member 33 extends therefrom in a direction toward the central portion of the cross member 16. An arm 37 extends downwardly from the lever arm 36 and has a tension member, such as a coil spring 38 interposed between the end of said arm and the frame for supporting the winding drum 24. The coil spring 38 is so arranged as to move the bell crank member 33 in a direction opposite to which it moves when engaging the pawl 30 with the ratchet teeth 29 and rotating the winding drum 24.

A shield 40, herein shown as being formed in the shape of a segment of a circle and having an outwardly extending flange 41 formed integral therewith, is freely carried on the shaft 23 for pivotal movement with respect thereto and is disposed adjacent the outer side of the bell crank member 33. The flange 41 on the shield 40 acts as a cam and is adapted to be engaged by a roller 42 on the outer end of the pawl 30 so that said roller may engage and ride along the outer periphery of the flange 41 and hold the pawl 30 in a disengaged position with respect to the ratchet teeth 29. A tension spring 43 is connected to the end of the shield 40 opposite the flange 41 and is interposed between said shield and the frame of the winding drum 24 in such a manner that said spring will tend to engage said shield with the roller 42. A flexible member 44 is secured to an arm 44a extending outwardly from the shield 40 in a suitable manner for moving said shield against the tension spring 43 and permitting the roller 42 to be disengaged from the flange 41. Thus when it is desired to rotate the drum 24 and the bell crank member 33 is reciprocably driven, the application of tension on the flexible member 44 will pivot the shield 40 about the axis of the shaft 23, which will permit the roller 42 to be disengaged from the flange 41. The number of teeth which the pawl 30 may move the winding drum 24 per stroke of the bell crank member 33 is thus controlled by movement of the shield 40, effected by tension on the flexible member 44 so that the pawl 30 may move said winding drum a distance of one, two, three or more teeth per stroke of said bell crank member depending upon the length of stroke of said bell crank member. In order to stop rotation of the winding drum 24, tension on the flexible member 44 is released which permits the roller 42 to engage and ride along the flange 41 and holds the pawl 30 in a disengaged position with respect to the ratchet teeth 29.

Referring now in particular to the means for reciprocably moving the bell crank member 33 upon reciprocable movement of the conveyor pan 10 and several other of the novel features of my

invention, the lever arm 36 of said bell crank member has a forked outer end which is provided with a plurality of apertures 45, 46 and 47, spaced inwardly from the outer end thereof in the order enumerated. A bell crank member 48 is journaled on the cross member 16 for pivotal movement with respect thereto between the brackets 19, 19. A link 49 is pivotally connected between one lever arm 50 of the bell crank member 48 and one of the apertures 45, 46 or 47 depending upon the length of stroke of the conveyor pan 10.

The link 49 is herein shown as comprising a universal coupling 51 pivotally connected to the lever arm 36, a universal coupling 52 pivotally connected to the lever arm 50, a threaded rod 53 connecting said couplings together and held from movement with respect thereto by means of nuts 54, 54 threaded thereon and abutting the inner ends of said universal couplings. The link 49 is thus capable of adjustment to take care of varying positions of adjustment of the cross member 16 with respect to the ground.

A link 55 is provided for connecting another lever arm 56 of the bell crank member 48 with the conveyor trough 10. The link 55 includes a clevis 57 pivotally connected to the lever arm 56 of the bell crank member 48, a clevis 58 pivotally connected to a connecting member 59 detachably connected to the underside of the conveyor trough 10, a threaded rod 60 adjustably connecting said clevises together and nuts 61, 61 for locking said clevises in various positions of adjustment with respect to each other along said rod. The length of the connecting link 55 may thus be adjusted to take care of varying lengths of pan lines or positions of the pan 10 with respect to the cross member 16.

A flexible cable 62 is adapted to be connected to the winding drum 24 and may be trained therefrom around a suitable sheave 63 to a coupler of one of the cars 11. Thus when tension is applied to the flexible member 49, the winding drum 24 may be driven by the conveyor trough 10, as the amount of tension applied to said flexible member is increased the speed of rotation of said winding drum may be increased and when tension is released from said flexible member rotation of said winding drum may cease.

It may thus be seen that a car puller of a new and improved construction has been provided wherein the winding drum is adapted to be rotatably driven by means of a shaker conveyor pan line, which car puller is arranged in such a manner that the conveyor trough is supported on the frame work which supports the car puller and holds it from movement with respect to the ground, and that the device of my invention is so arranged that reciprocable movement of the conveyor trough is transferred into rotational movement through a simple and novel system of links and levers in an improved and efficient manner.

While I have herein shown and described one form in which my invention may be embodied, it will be understood that the arrangement of the various parts and the construction thereof may be altered or changed without departing from the spirit and scope thereof. Furthermore, I do not wish to be construed as limiting myself to the specific embodiment illustrated, excepting as it may be limited to the appended claims.

I claim as my invention:

1. In combination with a shaker conveyor, a reciprocably movable conveyor pan, a winding

- drum, and means for transferring the reciprocable movement of said conveyor pan into rotary movement for driving said winding drum including a member supported above the ground 5 and extending transversely of said conveyor pan, a bell crank member journaled thereon, a connection from one lever arm of said bell crank member to said conveyor pan, and a connection from the other lever arm of said bell crank member to said winding drum. 10
2. In combination with a shaker conveyor, a reciprocably movable conveyor pan, a support, a winding drum carried thereby, and means connectible with said conveyor pan for rotating said winding drum including a pawl and ratchet device, a bell crank member, a connection from one lever arm of said bell crank member to said pawl and ratchet device, and a connection from said conveyor pan to said other lever arm of said bell 15 crank member. 20
3. In a car puller and in combination with a shaker conveyor, a conveyor pan, a support including a base, a winding drum carried thereby, means for holding said base in position on the ground comprising a plurality of jacks interposed between said base and the mine roof, a cross member connecting said jacks together, support means on said cross member for supporting said conveyor trough for reciprocable movement with respect thereto, and means driven from said conveyor trough for rotatably driving said winding drum comprising a pawl and ratchet device associated with said drum, a bell crank member carried by said cross member for pivotal movement with respect thereto, a connection from one lever arm of said bell crank member to said pawl and ratchet device and a connection from said other lever arm of said bell crank member to said conveyor trough. 25
4. In a winding device and in combination with a shaker conveyor, a conveyor pan, a support therefor including a base, a plurality of adjustable jacks interposed between the mine roof and bottom, a cross member connecting said jacks together and roller devices supported by said cross member for engaging the under surface of said conveyor pan, winding means carried by said support including a winding drum and drive means cooperating with said support and driven by said shaker conveyor for driving said winding drum including a ratchet operatively connected with said drum, a pawl adapted to engage said ratchet, means for intermittently engaging said pawl with said ratchet including a lever arm pivotally movable in a vertical plane, a bell crank member journaled on said cross member, a connection from one lever arm of said bell crank member to said lever arm and an operative connection from said shaker conveyor to the other lever arm of said bell crank member. 30
5. In an apparatus of the class described, a winding drum, a ratchet associated therewith, a bell crank member movable about an axis coaxial with the axis of rotation of said winding drum, a reciprocably movable conveyor pan, and a drive connection from said conveyor pan to said bell crank member for translating the reciprocable movement of said pan into pivotal movement comprising a second bell crank member, a connection from said conveyor pan to one lever arm of said second bell crank member, and a connection from the other lever arm of said second bell crank member to said first bell crank member. 35
6. In an apparatus of the class described, a winding drum, a ratchet associated therewith, a bell crank member movable about an axis coaxial with the axis of rotation of said winding drum, a reciprocably movable conveyor pan, and a drive connection from said conveyor pan to said winding drum for translating the reciprocable movement of said pan into rotatable movement comprising a second bell crank member, a connection from said conveyor pan to one lever arm of said second bell crank member, and an adjustable connection from the other lever arm of said second bell crank member to said first bell crank member. 40
7. In an apparatus of the class described, a winding drum, a ratchet associated therewith, a bell crank member movable about an axis coaxial with the axis of rotation of said winding drum, a reciprocably movable conveyor pan, and a drive connection from said conveyor pan to said winding drum for translating the reciprocable movement of said pan into rotatable movement comprising a second bell crank member, a connecting link interposed between one lever arm of said second bell crank member and said conveyor pan and another connecting link operatively connecting the other lever arm of said second bell crank member with said first bell crank member. 45
8. In an apparatus of the class described, a winding drum, a ratchet associated therewith, a bell crank member movable about an axis coaxial with the axis of rotation of said winding drum, a reciprocably movable conveyor pan, and a drive connection from said conveyor pan to said winding drum for translating the reciprocable movement of said pan into rotatable movement comprising a second bell crank member, an adjustable connecting link interposed between one lever arm of said second bell crank member and said conveyor pan and an adjustable operative connection between said other lever arm of said second bell crank member and said first bell crank member. 50
9. In an apparatus of the class described, a winding drum, a ratchet associated therewith, a bell crank member movable about an axis coaxial with the axis of rotation of said winding drum, a reciprocably movable conveyor pan, means for supporting said conveyor pan above said winding drum for reciprocable movement with respect thereto including a bottom plate, a pair of jacks interposed between the mine roof and said plate, a cross member carried thereby, and anti-friction roller devices carried by said cross member and engaging the under surface of said conveyor trough, said support means also forming a support means for said winding drum, and a drive connection from said conveyor pan to said bell crank member for translating the reciprocable movement of said pan into rotatable movement for driving said drum including a second bell crank member journaled on said cross member, a connection from said conveyor pan to one lever arm of said second bell crank member and a connection from the other lever arm of said second bell crank member to said first bell crank member. 55
10. In an apparatus of the class described, a winding drum, a ratchet associated therewith, a bell crank member movable about an axis coaxial with the axis of rotation of said winding drum, a reciprocably movable conveyor pan, means for supporting said conveyor pan above said winding drum for reciprocable movement with respect thereto including a bottom plate, a pair of jacks 60

- interposed between the mine roof and said bottom plate, a cross member carried thereby and mounted for adjustment therealong and anti-friction roller devices carried by said cross member and engaging the under surface of said conveyor trough, said means for supporting said conveyor pan also forming a support means for said winding drum, and a drive connection from said conveyor pan to said bell crank member for translating the reciprocable movement of said pan into rotatable movement for driving said drum including a second bell crank member journaled on said cross member, an adjustable connecting link connected between said conveyor pan and one lever arm of said second bell crank member and an adjustable connecting link connected between said bell crank members.
- 5 10 15 20 25 30
11. In an apparatus of the class described, a winding drum, a ratchet associated therewith, a bell crank member movable about an axis coaxial with the axis of rotation of said winding drum, a reciprocably movable conveyor pan, means for supporting said conveyor pan above said winding drum for reciprocable movement with respect thereto including a bottom plate, a pair of jacks interposed between the mine roof and said bottom plate, a cross member carried thereby and anti-friction roller devices carried by said cross member and engaging the under surface of said conveyor trough, said means for supporting said conveyor pan also forming a support means for

said winding drum, and a drive connection from said conveyor pan to said bell crank member for translating the reciprocable movement of said pan into rotatable movement for driving said drum including a second bell crank member journaled on said cross member, an adjustable connecting link connected between said conveyor pan and one lever arm of said second bell crank member and an adjustable connecting link connected between said bell crank members.

12. In an apparatus of the class described, a winding drum, a ratchet associated therewith, a bell crank member movable about an axis coaxial with the axis of rotation of said winding drum, a reciprocably movable conveyor pan, means for supporting said conveyor pan above said winding drum for reciprocable movement with respect thereto including a bottom plate, a pair of jacks interposed between the mine roof and said bottom plate, a cross member carried thereby and anti-friction roller devices carried by said cross member and engaging the under surface of said conveyor trough, said means for supporting said conveyor pan also forming a support means for said winding drum, and a drive connection from said conveyor pan to said bell crank member for translating the reciprocable movement of said pan into rotatable movement for driving said drum including a second bell crank member journaled on said cross member.
